UNITED STATES PATENT OFFICE.

DAVID V. STRATTON, OF NEW YORK, N. Y.

DESIGN FOR COMBINATION WRITING DESK AND RADIOCABINET.

Application filed January 26, 1925. Serial No. 12,145. Term of patent 3½ years.

To all whom it may concern:

Be it known that I, DAVID V. STRATTON, a citizen of the United States, residing at New York, in the county of New York and State of New York, have invented a new, original, and ornamental Design for Combination Writing Desk and Radiocabinet, of which the following is a specification, reference being had to the accompanying drawing, forming part thereof.

The figure is a perspective view of a combination writing desk and radio cabinet, showing my new design with the doors for the compartments for the radio set, loud speaker and batteries closed.

I claim:

The ornamental design for a combination writing desk and radio cabinet, as shown.

DAVID V. STRATTON,
